US00D626121S

(12) **United States Design Patent**
Richardson et al.

(10) **Patent No.:** **US D626,121 S**
(45) **Date of Patent:** **** Oct. 26, 2010**

(54) **CASE**

(75) Inventors: **Curtis Richardson**, Fort Collins, CO (US); **Jamie Johnson**, Fort Collins, CO (US); **Stephen Willes**, Fort Collins, CO (US); **Travis Smith**, Fort Collins, CO (US)

(73) Assignee: **Otter Products, LLC**, Fort Collins, CO (US)

(**) Term: **14 Years**

(21) Appl. No.: **29/359,899**

(22) Filed: **Apr. 16, 2010**

(51) **LOC (9) Cl.** **14-03**

(52) **U.S. Cl.** **D14/250**

(58) **Field of Classification Search** D14/140, D14/142, 167, 217, 218, 240, 242, 248, 250–253, D14/299, 341–347, 440; D3/200–201, 215, D3/218–219, 226, 228, 269, 301, 272–273, D3/276, 294; D13/103, 107–108, 119; 220/4.02; 224/191, 240, 241, 245, 682–683; 248/206.2–206.4, 248/220.21, 279.1, 309.1; 361/679.3, 679.56; 379/420.04, 426, 433.11, 446–447, 454, 379/455; 455/575.1, 575.6, 575.7, 575.8, 455/575.9; 190/100; 206/305, 320

See application file for complete search history.

Assistant Examiner—Carla Jobe Wright

(57) **CLAIM**

The ornamental design for a case, as shown and described.

DESCRIPTION

FIG. 1 is a front isometric view of a case showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines immediately adjacent the claimed surfaces represent the bounds of the claimed design. All other broken lines are directed to environment. The broken lines and unshaded regions within the broken lines form no part of the claimed design.

1 Claim, 6 Drawing Sheets
